UNITED STATES PATENT OFFICE.

JAMES H. BLESSING AND CHARLES H. OVERTON, OF ALBANY, NEW YORK;
SAID OVERTON ASSIGNOR TO SAID BLESSING.

DUPLEX STEAM-ENGINE.

SPECIFICATION forming part of Letters Patent No. 451,904, dated May 5, 1891.

Application filed September 26, 1889. Serial No. 325,118. (No model.)

To all whom it may concern:

Be it known that we, JAMES H. BLESSING and CHARLES H. OVERTON, both of the city and county of Albany, in the State of New York, 5 have invented new and useful Improvements in Duplex Steam-Engines, of which the following is a specification.

Our invention relates to improvements in that class of steam-engines in which two independent steam cylinders, each provided with a reciprocating piston, are employed to transmit their power to a single shaft; and the object of our invention is to simplify the construction in such manner that the power derived from both pistons will be applied directly to a single crank, and so that the slide-valves of both engines will be properly operated by a single eccentric, the parts being so constructed that the stroke of the pistons will be greater than the throw of the crank to which they are connected, whereby we are enabled to attain a higher rate of piston speed with a given number of strokes than can be obtained from an engine of the ordinary construction having the same length of crank, and the distance traveled by either piston while the engine-shaft is making a complete revolution will approximate the circumference of the circle described by the center of the crank-pin of said engine-shaft. By our construction we are enabled to attain with one crank and crank-shaft the full effect of two engines connected to two cranks fixed at right angles on the same shaft—that is to say, when the piston of either engine has attained its mid-stroke position the piston of the opposite engine will be at one of the extreme points of its stroke, and we are also enabled to operate the valves of both of the engines by means 40 of a single eccentric that is common to the two engines.

We attain our object by the mechanism illustrated in the accompanying drawings, which are herein referred to and form part 45 of this specification, and in which—

Figure 1 is a partial plan view of our duplex-engine adapted to operate duplex-pumps, the balance-wheel and steam-chests being removed to expose the slide-valves and their 50 operating mechanism, one of the pistons being at the extremity of its movement in one direction and the other approaching a like

position. Fig. 2 is a like view showing the crank at one of its ordinary dead-center points, the two pistons moving in opposite 55 directions. Fig. 3 is a transverse section of Fig. 1 at the line X X. Fig. 4 is an enlarged and detached plan view of the triple arm which connects the two piston-rods with the crank-pin, and Fig. 5 is a skeleton diagram 60 showing the positions of the triple arm at eight different but equally-spaced points in the circle described by the center of the crank-pin.

While we have shown in the drawings our 65 invention as applied to a horizontal form of engine, it should be understood that it is equally applicable to any other form of duplex engines.

As represented in the drawings, A designates the steam-cylinders of our engine, which, for the sake of convenience, will be referred to as the right and left engine, as viewed by a person facing the outer end of said cylinders. The two cylinders may be made in one 70 piece, as in the drawings, or separately with the usual steam and exhaust ports and passages, and they are provided with the usual pistons employed in reciprocating engines.

B is the frame or bed-plate of the engine, 80 which in the form shown in the drawings also forms the heads for the steam-cylinders A and the pump-cylinders C, but the form of said frame may be changed to suit the particular style of engine required.

D is a guide-bar which extends to opposite ends of the frame B, and is provided with parallel sides 1, which form an open guide for parts hereinafter described. Said guide-bar is also provided with a boss 2, which 90 forms one of the bearings for the crank-shaft E, the other bearing 3 for said shaft being formed on the frame B. The crank-shaft E is provided with a crank F, whose crank-pin 4 (indicated by dotted lines in the drawings) receives the motion imparted from both 95 pistons of the engine.

G designates the piston-rods of the engine. The outer end of each of said piston-rods is secured in a cross-head H, to the opposite end 100 of which in the form of engine shown in the drawings a pump-plunger I is secured, said plunger forming a guide, which relieves the piston-rod of a lateral strain to which it is

liable to be subjected. Said cross-head when preferred and in other forms of our engines may be provided with any other form of guide. The cross-head H is preferably made with an opening 5, over which at one end lugs 6 extend on the upper and lower sides, and a wrist-pin 7 is fixed in said lugs to form a journal for one end of a connecting-link J, which is located in the opening 5, so as to bring said link on a level with the center line of the piston-rod, and thereby relieve the latter from the strain which would arise from fixing the wrist-pin either on the upper or lower side of the cross-head.

15 K is a triple arm by which power and motion from the pistons of the engine are transmitted to the crank-shaft E. Said triple arm is provided with an opening 8, which is equidistant from each of its end centers. Two branches of said triple arm range in direct line with each other and the other branch forming a right angle therewith. The ends of the first-named branches are bifurcated to form lugs 9, that extend over and under the cross-head H, and each pair of said lugs is provided with a wrist-pin 10 to receive the end of the corresponding link J, and thereby effect the connection of the cross-heads with the triple arm K.

30 L is a guide-block that is fitted to slide back and forth in the lower part of the opening formed in the guide-bar D by the parallel sides 1. Said guide-block is provided with a stud or pivot 11, which fits into the opening 8 in the triple arm K and forms a fulcrum on which the latter receives a vibratory motion by reason of its connection to the crank F, the single arm of the triple arm K being connected to the crank-pin of said crank by a split box 12 or other suitable or analogous means and the sliding movement of the guide-block L in the guide-bar D permitting the triple-arm K to follow in a direct line the movement produced by the throw of said crank.

45 M designates the slide-valves for governing the admission and exhaustion of steam into and out of the cylinders A. Said valves are secured to valve-rods 13, which are jointed to the opposite ends of the two direct branches of a triple arm N that corresponds essentially to the triple arm K, but whose single arm is provided with an eccentric strap or hoop 14, which is fitted to engage upon an eccentric O, fixed on the shaft E. The triple arm N is provided with a central opening that is fitted to engage on a pivot 15, fixed in a sliding guide-block P, which moves in the upper part of the opening formed in the guide-bar D, said guide-block and pivot forming a shifting fulcrum for the triple arm N, whereby the latter is enabled to follow the movements imparted thereto by the eccentric O.

60 Q is a balance-wheel that is secured to the shaft E for the purpose which said wheels are commonly employed on steam-engines.

R is an air-chamber (shown in Fig. 3) that

is provided for the pumps attached to and operated by the engines shown in the drawings. Said pumps do not form any part of our present invention, and therefore do not require further illustration or description.

70 The operation of our engines will be understood by the following description, in connection with the diagram shown in Fig. 5: Premising that the valve-operating mechanism is adjusted to run the engines so that the crank-shaft E will revolve in the direction indicated by the curved arrows in Figs. 2 and 5, and that when the crank-pin is in the positions 1 8c and 5 on the line of the path of said crank-pin on the diagram shown in Fig. 5, in which positions the crank F will be, at the two extreme points of its throw, in a line parallel to the center line of the cylinders A; or in the positions commonly known as the "dead-centers" in engines of ordinary construction the triple arm K will attain positions where its two direct branches will stand at a right angle to the center line of the cylinders, and the pistons of the two engines will be in corresponding positions, the position of said pistons corresponding to the point 1 on the path of the crank-pin in said diagram, being indicated by dotted lines in Fig. 2, equidistant from the 90 cylinder-heads nearest the crank-shaft.

95 When the crank-pin has reached the point 2 on its path, the piston of the right engine will have moved backward to its mid-stroke position and the piston of the left engine will have moved forward to the extreme end of its stroke toward the crank-shaft, and it will be seen by reference to said diagram that in moving to the position last named the piston of the left engine will have moved a distance 100 equal to the distance between the points 1' and 2' on the lower line of said diagram beyond the termination of its stroke in that direction if the engine was connected directly to the crank in the usual manner. After 105 passing the point 2 and until the point 4 on the path of the crank-pin is reached the pistons of both engines will move in the same direction, toward the cylinder-heads farthest from the crank-shaft.

110 When the point 4 has been reached, the piston of the right engine will be at the extreme end of its stroke in the direction last referred to, wherein the stroke of said piston will exceed the stroke of a piston connected directly to a crank in the ordinary manner by a distance equal to that between the points 4" and 5" on the upper line of the diagram, and the piston of the left engine will be at its mid-stroke position. When the crank-pin has reached the point 5 on the 115 path of said crank-pin, the two pistons will stand opposite each other in the end of the cylinders farthest from the crank-shaft; but neither of said pistons will then be at that extremity of its stroke. When the crank-pin has 120 reached the point 6, the piston of the left engine will have attained the extremity of its stroke in the direction farthest from the crank-shaft, the movement in that direction exceeding the 125 130

throw of the crank in the same direction by a distance equal to the distance between the points 5' and 6' on the lower line of the diagram, and the piston of the right engine will 5 be at its mid-stroke position. While the crank-pin is passing from the point 6 to 8 the pistons of both engines will move in the same direction, and at the last-named point the piston of the right engine will have attained the 10 extremity of its stroke toward the crank-shaft, again exceeding the stroke due to the throw of the crank when connected directly to the piston, as hereinbefore described, and the piston of the left engine will again be at its 15 mid-stroke position; and while the crank-pin is moving from 8 to 1 the piston of the right engine will move backward and the piston of the left engine will move forward until both have attained the initial positions herein- 20 above described, and thereby a complete double stroke of both pistons will be accom- plished and the parts in position for a repetition of the operations just described. The triple arm N transmits the motion of the eccentric O to the slide-valves of both engines in such manner that the admission and 25 exhaustion of steam in both engines will occur at exactly the right times to produce the operations of the latter above described.

30 In the drawings the triple arm K is made with all its branches of the same length from the pivotal center of said arm to the point of connection of each branch. By such a construction the pistons will have a stroke that 35 is slightly in excess of the circumference of the circle described by the center of the crank- pin; but by shortening the branch of said arm that is connected to the crank-pin, mak-

ing the length of said arm about five-sixths of the others, the stroke of the pistons will conform very closely to the circumference of said circle. 40

Instead of applying the power of the engines for operating pumps in the manner illustrated in the drawings, power may be 45 taken directly from the crank-shaft in the manner commonly followed in obtaining motion from steam-engines, and our engines in an inverted form will have advantages for driving screw-propellers for marine purposes. 50

What we claim as our invention, and desire to secure by Letters Patent, is—

In a duplex steam-engine, the combination of two steam-cylinders, which are each provided with the usual piston and piston-rod, a 55 shaft provided with a single crank, and two triple arms, each comprising a continuous beam having a single arm projecting at right angles therefrom and each being pivoted at the junction of its single arm with its continuous beam to shifting fulcrums, which are fitted to move in guides, one of said triple arms being connected at its opposite ends to the piston-rods of the engines and its single arm being connected to the single crank of an en- 60 gine-shaft, and the other triple arm being connected at its opposite ends to the valve-rods and its single arm being connected to a single eccentric on the shaft of said engine, as and for the purpose herein specified. 65
